UNITED STATES PATENT OFFICE.

JOHN W. EVANS, OF CLEVELAND, OHIO.

APPARATUS FOR EVAPORATING NAPHTHA.

SPECIFICATION forming part of Letters Patent No. 449,215, dated March 31, 1891.

Application filed May 10, 1890. Serial No. 351,275. (No model.)

To all whom it may concern:

Be it known that I, JOHN W. EVANS, of Cleveland, in the county of Cuyahoga and State of Ohio, have invented certain new and useful Improvements in Apparatus for Evaporating Naphtha; and I do hereby declare the following to be a full, clear, and exact description of the invention, such as will enable others skilled in the art to which it pertains to make and use the same.

My invention relates to improvements in evaporators designed more especially for evaporating naphtha from oil; and it consists in certain features of construction and in combination of parts hereinafter described, and pointed out in the claims.

In the naphtha process of extracting oil, for instance, from seeds the seeds are ground and placed in large percolators, and the latter are then filled with hot naphtha for extracting the oil. At the end of this process the united oil and naphtha are drawn from a percolator into an evaporator, where the naphtha is evaporated, and the vapor thereof passes to a condenser, from whence the liquid naphtha is returned to its tank to be again used for the same purpose. As the percolator is likely to hold, say, a thousand bushels of meal, more or less, and at the same time to be charged with, say, a hundred and fifty barrels (more or less) of naphtha, and as there is likely to be a number of such percolators in constant operation, it is evident that the evaporator must be of large size and constructed so as to do its work with dispatch.

In evaporating the naphtha only a moderate heat should be applied, for the reason, first, that too much heat will scorch and injure the oil, and, second, it is not desirable or prudent to heat naphtha to a high degree. It will therefore be understood that the evaporator should be so arranged and be provided with such appliances that the naphtha may be quickly evaporated with the minimum degree of heat. To this end I have devised the evaporator and connected mechanism illustrated in the accompanying drawings.

Figure 1 is a view in perspective. Fig. 2 is an elevation in longitudinal section on line x x , Fig. 3. Fig. 3 is an elevation in transverse section on line y y , Fig. 2.

A represents the evaporator, constructed, preferably, of boiler-iron and of approximately the form shown and of such size as will have the necessary capacity for holding a batch of oil and naphtha from at least one percolator. At the top of the evaporator the walls thereof are extended laterally in one direction, the one above the other, as shown at A' A'' , these walls connecting with a semicircular plate A^3 . The end walls and plate A^3 are provided with flanged openings at a , leading into eduction-pipes a' , that may be attached at either or both ends of the evaporator and at the side for conducting the naphtha-vapor to a condenser. (Not shown.) With such construction it is evident that the naphtha-vapor may have free passage to the eduction pipe or pipes a' , and has not to travel lengthwise of the evaporator to find an outlet, as would be the case were there one or more eduction-pipes connected with the top of the evaporator. On the inside of the evaporator, and located near the bottom thereof, is a coil of steam-pipes B, and just above this coil is located a series of perforated steam-pipes B' for admitting live steam into the liquid in the evaporator. Pipes B' usually connect with the coil B by valves B^2 to control or shut off the steam to or from pipes B' . Located above pipes B' are agitators, each comprising a large heavy axial tube C, bearing a series of hollow radial arms C' , these arms consisting, preferably, of tubes with caps to close the outer ends, these arms being screwed into threaded holes in tubes C. Tubes C extend out through suitable boxes and stuffing-boxes at the ends of the evaporator, the two tubes C being intergeared, preferably, as shown at c c , so as to turn in opposite directions, and on one of these tubes is mounted a driving-pulley C^2 . The one end of each tube C connects with a steam-pipe, and the other end is usually reduced in size and provided with a cock, as shown at C^3 , by manipulating which cock a slight discharge of steam is had to give circulation of steam through the agitators to keep them heated.

D D are troughs extending approximately the internal length of the evaporator, these troughs being arranged, preferably, substantially as shown, each trough being heated by

steam for the purpose of heating the upper section of the evaporator of the inclosed chamber to prevent, as far as possible, the condensation of the naphtha-vapor and to catch any condensed naphtha that there may be and revaporize the same by means of the heat of the troughs. These troughs are preferably constructed with double walls, as shown more clearly in Fig. 2, so that steam may be admitted into the chambers of each trough. The troughs are located, as shown, some distance apart, so that the vapor may have free passage between the troughs, and so that the troughs will catch any condensed naphtha from above. A system of pipes and return-bends connect the different troughs, and these are supplied with steam through pipe *d*, leading, preferably, to and connecting with the coil of pipe *B*, although these troughs may be supplied with steam from other source, if for any reason it is found more convenient to do so. The last trough of the series should be provided with a cock, as shown at *d'*, to give circulation of steam through the troughs. A trough constructed with a single wall and having a steam-pipe extending lengthwise and resting on the internal bottom thereof would answer fairly well, but would not be so effective in heating the upper section of the evaporator. Hence the construction shown, although more costly, is preferred.

E is a vacuum-valve opening inward to prevent the evaporator from collapsing in case of a partial vacuum being formed therein by the vapors being condensed too suddenly in the condenser.

F is a glass gage of ordinary construction for showing the depth of liquid in the evaporator. There is a large opening at one end of the evaporator for introducing the coils of pipe, this opening being closed by removable plate *G*, portions of which may be seen in Fig. 1; also, is provided a man-hole and plate, (shown at *H*.) Large sight-holes are provided at *I* on either end of the evaporator, these orifices being closed by glass plates that admit light inside the evaporators, and through which the operation going on inside the evaporator may be inspected.

J is a pipe for admitting the material to the evaporator, and *K* is a pipe for drawing off the oil.

L is an oil-well of ordinary construction, consisting of outer and inner tubes joined at the outer ends, the inner end of the inner

tube being closed and the inner end of the outer tube extending into the container. A thermometer *l* is inserted in the inner tube to determine the temperature of the liquid in the still.

In operating the device, the evaporator having been charged with a mixture of oil and naphtha, say, to near the line of the bottom troughs, first steam is admitted to coil *B* to heat the liquid. A large per cent. of the naphtha is readily evaporated by this means. Next steam is admitted to the perforated pipes, and the agitator is also set in motion, being heated meantime with steam. This is continued until the naphtha is entirely evaporated from the oil, which may be readily determined by observing the discharge of the condenser to see when the condensed naphtha ceases to flow from the condenser, leaving a discharge only of water from the condensed steam. The oil is then drawn off through pipe *K*, and the evaporator is again charged through pipe *J* and is ready for another operation.

What I claim is—

1. The combination, with an evaporator, of one or more horizontal steam-heated troughs located internally along the upper section of the evaporator and adapted to catch and retain condensed vapor and revaporize the same, substantially as set forth.

2. The combination, with an evaporator, of horizontal troughs located in the evaporator, substantially as indicated, and adapted to catch and retain condensed vapor and revaporize the same, such troughs having double walls inclosing steam-chambers, and pipes connected with these chambers for supplying steam thereto, substantially as set forth.

3. The combination, with an evaporator having a heating-coil and perforated steam-pipes arranged substantially as indicated, of agitators comprising axial pipes having attached hollow radial arms with appliances for introducing steam to such agitators, the latter being intergeared to turn in opposite directions, substantially as set forth.

In testimony whereof I sign this specification, in the presence of two witnesses, this 24th day of April, 1890.

JOHN W. EVANS.
